UNITED STATES PATENT OFFICE.

FRANK C. GONZALES, OF TRAER, IOWA.

GAS-ENGINE VALVE.

1,082,320.

Specification of Letters Patent. Patented Dec. 23, 1913.

Application filed January 11, 1912. Serial No. 670,580.

To all whom it may concern:

Be it known that I, FRANK C. GONZALES, a citizen of the United States, residing at Traer, in the county of Tama and State of Iowa, have invented a new and useful Improvement in Gas-Engine Valves, of which the following is a specification.

My invention is an improvement in gas engine valves, and has for its object, the provision of a direct acting valve for use with engines of the character specified, which will be comparatively noiseless in operation, simple in construction and in operation, accessible for cleaning or the like, and having a large bearing surface, so that wear is reduced to a minimum.

In the drawings, Figure 1 is a partial longitudinal section of the cylinder of an engine provided with the improvement. Fig. 2 is a front view of the same. Fig. 3 is a perspective view of the guide plate. Fig. 4 is a similar view of a valve. Fig. 5 is a similar view of the cover plate. Fig. 6 is a side view of the cam, and Fig. 7 is an edge view of the cam.

In the embodiment of the invention shown in the drawings, the cylinder 1 of the engine is jacketed, as indicated at 2, and the usual piston 3 is slidable in the cylinder. A cam shaft 4 is journaled in sectional bearings 5 on the cylinder, and a double cam wheel 6 is secured to the shaft.

The cam is provided with cam grooves 7 and 7^a, in its opposite faces, and each groove is engaged by a roller 8—8^a respectively. The rollers 8 and 8^a are journaled on pins 9, extending laterally from the ends of valve stems 10 and 10^a the roller 8 being connected to the stem 10 and the roller 8^a to the stem 10^a. The stem 10 is connected to a slide valve 11, and the stem 10^a is connected to a slide valve 11^a.

The valves 11 and 11^a are slidable in recesses or guideways 13 and 13^a respectively, formed in the outer face of a guide plate 12. The guideways are parallel, and are spaced apart laterally from each other, and the plate 12 is provided with threaded openings 14 at each side edge and between the guideways.

The cylinder 1 is flattened on the side adjacent to the cam shaft, to receive the plate 12, and a cover plate 15 is arranged on the outer face of plate 12. The cover plate 15 covers the upper portions of the guideways, and the cylinder is provided with a pair of

ports 16 and 16^a at the flattened surface. The plate 12 has ports 17 and 17^a, registering with the ports 16 and 16^a.

The plate 15 has ports 19 and 19^a in register with ports 17 and 17^a, and the said plate is provided with openings 20 registering with the openings 14 of the guide plate 12. Cap screws 21 are passed through the openings 14 and 20, and engage threaded recesses 65 in the cylinder for holding the plates 12 and 15 in place.

The upper end of each stem 10 is flattened laterally, as shown 22, and the flattened portion 22 of each stem is secured to the outer 70 face of the adjacent valve by rivets or screws 23. The cover plate 15 is cut away at the lower end of each guideway, as indicated at 24, to receive the portion 19 of the adjacent stem.

Each of the stems passes through a guide adjacent to the cam wheel, the said guides being formed between bars 25 and 26, secured to upwardly extending arms 27 on the bearings 5. The bars are recessed or grooved 80 transversely to receive the stems, and are secured together and to the arms by means of screws 28.

Each of the valves 11 and 11^a, is provided with a port 29, which when the valve is in 35 a certain position places the port of the guide plate adjacent to the valve in communication with the adjacent port of the cover plate. At all other times the valve closes the said communication. The port 16 90 is the inlet for the cylinder and the port 16^a is the exhaust port.

The cam shaft 4 is driven from the crank shaft of the engine, by any suitable connection, and at a speed, one half that of the 95 crank shaft. The grooves 7 and 7^a are so arranged, that the roller 8 or 8^a as the case may be, is in the concentric portion thereof during three fourths of the travel of the cam during each rotation, and in the eccentric portion during one fourth of each rotation.

The grooves are so arranged with respect to each other, that when roller 8^a is in the eccentric portion of the groove 7^a to open 105 the exhaust, roller 8 is approaching the eccentric portion of groove 7, and enters the said portion when roller 8^a leaves the eccentric portion of groove 7^a. Thus valve 11^a is open during one stroke, valve 11 during 110 the next stroke, and both valves closed during the next two strokes. Both valves are

accessible, and have very large bearing surfaces, so that they do not become loose or ill fitting from wear, and always make a tight joint between the valve and cylinder.

5 In operation, after the working stroke, valve 11^a opens to permit the piston to drive out the products of combustion on the return stroke. As the piston commences to move outward after the return stroke, valve 10 11 opens and a charge is drawn into the cylinder. The return stroke of the piston compresses the charge, which is then ignited in the usual manner by the usual means.

I claim,

15 1. In an engine, a cylinder provided with an inlet and an exhaust port at the end remote from the crank shaft, a guide plate provided with ports registering with the ports of the cylinder, and with laterally spaced parallel guideways extending longitudinally of the cylinder, one of the ports 20 being in each guideway, a cover plate over

the guide plate, said cover plate having ports registering with the ports of the guide plate, a slide valve in each guideway, each valve having a port for placing the ports of the guide plate and cover plate in communication when the valve is at the end of its movement toward the crank shaft, and means for operating the said valves.

2. An engine of the character specified, comprising a cylinder having inlet and exhaust ports arranged alongside each other, superposed guide and cover plates having 35 registering ports and having a guideway between the plates at each port, and a slide valve in each guideway, each valve having a port for registering with the ports of the guide plate and the cover plate.

FRANK C. GONZALES.
